AIRCRAFT FLOATLIGHT

Herbert C. Clauser and Robert S. Long, Westerville, Ohio, assignors to Kilgore, Inc., Westerville, Ohio, a corporation of Ohio

Application February 7, 1957, Serial No. 638,759

6 Claims. (Cl. 102—7)

This invention relates to a signal device and more particularly to a float light which may be dropped from aircraft and ignited by impact with the water, and will burn for a predetermined period while floating upright on the surface of the water.

Heretofore aircraft float lights of this type have been proposed which consist of a wooden body weighted at one end and buoyant in water after dropping from a plane at 500 to 1000 feet altitude, having means for initiating a flame for night signaling and smoke for day signaling on the surface of large and deep bodies of water. Signals of this type in the past have consisted of wooden bodies made from special types of pine wood, having one or more circular channels or bores, each of which accommodated the insertion of a sealed, metal covered, combustible pyrotechnic element. The metal case covering this element had a low melting point which permitted the metal case to be destroyed during the burning of the element. As a result of this destruction, the longitudinal bore or channel in the wooden body became the container or nozzle that emitted the phosphorous vapor of the pyrotechnic element through an opening in one end of the wooden body which produced a burning of the gaseous product of the burning floatlight, resulting in the formation of a flame and smoke from the burning signal. There are many disadvantages to the use of wood bodies in floatlights, such as lack of uniformity in the wood, lack of dimensional stability, checks, cracks, etc.; however, up to the present time, a suitable signal housed in a metallic tube has not been found feasible.

It is therefore an object of the present invention to provide a signal device in which the pyrotechnic element is housed in a metallic container that will not be destroyed during burning of the signal, thereby eliminating the necessity of a wooden body.

It is a further object of the present invention to provide an aircraft floatlight with a long burning period that eliminates the necessity of a large number of individual candles with the large number of transitions of fuses to a series of candles.

It is a still further object of the present invention to provide an improved aircraft floatlight with a variable burning time that can be set prior to launching the signal.

A further object of the present invention is to provide an improved floatlight having a plurality of candles therein that can be burned either in parallel or in series.

A still further object of the present invention is to provide an aircraft floatlight provided with self-destroying means for sinking the signal after it has been used.

Other objects and the nature and advantages of the instant invention will be apparent from the following description taken in conjunction with the accompanying drawings, wherein:

Fig. 1 is a longitudinal sectional view of a floatlight in accordance with the present invention taken through substantially the center of the device;

2

Fig. 2 is a top plan view of the device;

Fig. 3 is a bottom plan view of the device;

Fig. 4 is a sectional view taken along the line 4—4 of Fig. 1;

Fig. 5 is a sectional view taken along the line 5—5 of Fig. 4;

Fig. 6 is a sectional view taken along the line 6—6 of Fig. 4 showing the projectile after it has pierced the outer casing;

Fig. 7 is an exploded perspective view of a portion of the device; and

Fig. 8 is an enlarged perspective view of the projectile and a portion of the outer casing.

Referring to the drawing, the numeral 10 designates an outer casing for the device that is a tubular member constructed preferably of metal which is open at both ends. The lower end as illustrated in Fig. 1 is crimped onto a metallic base member 12. The base member 12 is provided with a pair of openings therethrough 14, 15 which are of a smaller diameter at the lower end to accommodate a primer 16 therein. The base member 12 is relatively thick at the base thereof and acts as a ballast weight for causing the signal to drop heavy end downward and to maintain the signal upright while burning.

A lower cylindrical block 18 cut off at 17 along one edge along a chord of the section is located resting on the base member 12. The lower block 18, as best shown in Fig. 7, is provided with a pair of openings 19, 20 in alignment with the openings 14, 15 in the base member 12. The lower block 18 likewise is provided with four openings 21, 22, 23, 24 adapted to receive a guide pin 26 which screws into a threaded opening 28 in the base member 12, and a plurality of bolts 30. In addition to the six openings heretofore described extending through the thickness of the lower block 18, a bore 32 extends across the width of the block extending from the center of the cut off portion 17 to the opposite side of the block extending through the center thereof. This bore 32 is adapted to receive a scuttle gun assembly to be described hereafter. An opening 33 extends downwardly from the top of the block to the bore 32. A cylindrical shaped cut out 34 is located in the top surface of the block 18 extending downwardly therein for a portion of its thickness and centered above the opening 19 therethrough. A cut out channel 36 extends from the periphery of the cut out 34 to the other opening 20.

50 A center cylindrically shaped block 38 is located immediately above the lower block 18 resting thereagainst and is provided with four openings 39, 40, 41, 42 in alignment with the openings 21, 22, 23 and 24 in the lower block. A cylindrical opening 44 of the same diameter and aligned with the cut out portion 34 of the lower block is cut through the entire thickness of the block 38. A second cylindrical opening 46 of the same diameter as the opening 44 is cut out of the top surface of the block 38 extending downwardly for a portion of its thickness and centered above the opening 20 in the lower block. A smaller opening 48 in the center of the opening 46 aligned with the opening 20 in the lower block extends through the remainder of the thickness of the block 38. A cut out channel 50 extends from the periphery of the cut out opening 46 over to an opening 52 extending downwardly through the block in alignment with the opening 33 in the lower block 18.

60 A cover block 54 is located immediately above the center block 38 and is likewise provided with four openings 56, 57, 58 and 59 in alignment with the openings 39, 40, 41 and 42 in the center block. A cylindrical opening 60 of the same diameter and aligned with the

opening 44 of the center block is cut through the entire thickness of theb lock 54. A second cylindrical opening 62 of the same diameter and in alignment with the opening 46 in the center block is cut through the entire thickness of the block 54.

In assembling the device, the three blocks 18, 38, and 54 are maintained properly aligned by the bolts 30 which pass through the aligned holes in the three blocks which are held tightly pressed together by the nuts 31 screwed onto the ends of the bolts 30 as shown in Fig. 6. The guide pin 26 passes through aligned holes in the three blocks and screws into the threaded opening 28 in the base member 12. The three blocks may be made of a hard material such as Masonite or the like, and have approximately the same diameter as the inner diameter of the base member 12 into which they fit snugly. The strips of fuses to be described hereafter are inserted in the proper fashion in the openings and channels of the blocks prior to bolting together of the blocks and insertion in the base member 12.

A first pyrotechnic candle assembly 64 is located within the outer casing 10 and spaced therefrom as shown in Fig. 1 with its lower end extending through the cylindrical openings 60, 44 and 34 in the blocks heretofore described. The pyrotechnic candle assembly includes a lower base block 66 which may be made of Masonite or the like, having an opening 68 through the center thereof which is in alignment with the opening 19 in the lower block 18. A second opening 70 is provided throughout the thickness of the block 66. A cut out channel 72 extends from the opening 70 to the outer periphery of the block 66. The upper portion of the block 66 is of somewhat smaller diameter than the remainder of the block, thereby forming a shoulder 74 extending about the periphery of the block. A metal casting 76 of aluminum or the like extending the length of the candle assembly is attached to the lower base block 66 resting on the shoulder 74 thereon. Within the casing 76 are located an insulating lining tube 78 preferably of asbestos, and a lining tube 80 inwardly thereof, preferably made of a cellulosic fibrous material, as cardboard, all surrounding the pyrotechnic candle 82. The candle 82 is shown to be resting on a block 84 preferably of fire clay and a disc 86 which are located adjacent to the base block 66. The candle 82 is provided with a central channel or bore 88 extending the length of the candle. Located within the central bore 88 is a tube 90 of fibrous cellulosic material, such as cardboard. A strip of fuse 92 is located within the tube 90 extending from above the tube, through the tube 90, through the base block 66, opening 19 in the block 18 and thence into the opening 14 in the base member 12 adjacent to the primer 16.

Although not referred to hereafter, it should be noted that fuze terminals are used at every point where a fuze starts or ends.

At the upper end of the pyrotechnic candle 82 is mounted a container 94, covered with a cover 96, containing a starter composition 98. The upper end of the fuze 92 extends into the starter composition through an opening in the lower wall of the container 94.

Mounted on the casing 76 at the upper end thereof is an adapter 100 into which is fitted a stack member 102. A vapor barrier 103 is located in the adapter 100, which closes off the opening between the stack and the candle assembly. At the top of the stack member 102, the diameter thereof narrows at 104 to a smaller diameter tube 106 which is closed by a closure cup 108. The stock member 102 is lined with a liner 110 adjacent thereto.

At the lower end of the first pyrotechnic candle 82 is a passage 112 extending upwardly a short distance from the lower end of the candle 82. The passage 112 is in alignment with the opening 70 in the base block 66. A strip of fuze 114 extends from within the passage 112, through the opening 70 and channel 72 in the base

block 66, and thence across the channel 36 in the lower block 18 ending at a point adjacent to the opening 20 in the block 18.

A second pyrotechnic candle assembly 116 is located 5 within the outer casing 10 adjacent to and spaced from the first candle assembly and the outer casing 10. The lower end thereof extends through the cylindrical opening 62 in block 54 and the cylindrical opening 46 in the block 38. The second candle assembly 116 includes 10 a lower base block 118 preferably made of Masonite or the like, having an opening 120 through the center thereof which is in alignment with the opening 48 in the block 38. A second opening 122 is provided throughout the thickness of the block 118, with a cut out channel 124 extending from the opening 122 to the outer periphery of the block 118. The upper portion of the block 118 is of somewhat smaller diameter than the remainder of the block, thereby forming a shoulder 74 about the periphery of the block similar to the first candle 20 assembly. Similarly to the first candle assembly, the casing 76 is attached to the block 118 resting on the shoulder 74, and within the casing are located the insulating tube 78, lining tube 80, pyrotechnic candle 82, block 84, disc 86, central bore 88 and a tube 90 located 25 therein. A strip of fuse 126 extends throughout the tube 90, opening 120 in the base block 118 and ending in the opening 48 adjacent to the end of the fuse 114. The upper end of the second candle assembly is identical 30 to that of the first candle assembly including the identical stack arrangement and closure cup 108.

At the lower end of the second pyrotechnic candle is a passage 128 extending upwardly a short distance from the lower end of the candle. The passage 128 is in alignment with the opening 122 in the base block 118. A strip of fuse 130 extends from within the passage 128 through the opening 122 and channel 124 in the base block 118 and thence across the channel 50 in the block 38 and through the opening 52 therein, and through the opening 33 in the lower block 18, ending at a point adjacent to the bore 32 in the lower block 18.

A strip of fuse 131 extends from a point adjacent the end of fuses 114 and 126 downwardly through the opening 20 in the block 18 and ending in the opening 15 in the base member 12 adjacent the primer 16.

A closure cup 132 is located in the outer casing 10 near the upper end thereof, closing off the casing 10. A pair of openings are provided in the closure cup 132 into which are fitted closure stacks 134 which surround the upper end 106 of the stacks 102. A closure cap 136 is screwed onto the upper threaded outer surface of each of the closure stacks 134. As illustrated, a closing cork 138 and closing spacers 140 may be located between the closure cap 136 and the upper end of the stack 102.

At intervals along the length of the casing 10 are 55 located supports 142 which support the pyrotechnic candle assemblies. The space surrounding the candle assemblies within the outer casing 10 is void and permits of the signal being buoyant with the heavy end downward.

Attached to the lower surface of the base member 12 60 is the igniting mechanism. This mechanism will function upon impacts as low as from 15 feet above the water. A diaphragm housing 144 is screwed onto the base member 12 by screws 146. Located in the diaphragm housing 144 is a pair of diaphragms 146, 148 65 in alignment with the openings 14 and 15 respectively in the base member 12. The diaphragms are retained by diaphragm retainers 150. Enclosing the diaphragms are covers 152, 154 respectively, which are retained in place by forked clips 156. A striker 158 is located beneath each diaphragm in an opening in the diaphragm retainer. The strikers 158 are in alignment with and adjacent to the primers 16 housed in the base member 12. Upon actuation, the striker comes into direct contact with the primer.

A safety lug 160 is riveted to each diaphragm cover,

and for safety in shipment, a car seal 162 is attached through holes in the lug 160 and the clip 156 to prevent accidental removal of the clips during shipment.

Extending across the bore 32 in the lower block 18 is the scuttling gun assembly 164, best illustrated in Fig. 5. This assembly includes a barrel 166 extending virtually the entire diameter of the outer casing 10. At one end of the barrel 166 is located a breech cap 168 which is screwed onto the end of the barrel. A hole 170 extends through the breech cap 168 and barrel 166, and is so located as to be in alignment with the opening 33 in the lower block 18 and the end of the fuze 130. A gun wad 172 is located within the barrel at about the center of the length thereof, forming a chamber between the breech cap and the wad filled with black powder 174.

A projectile stop 176 is screwed onto the other end of the barrel 166. The projectile stop 176 has an opening 178 in the end thereof of smaller diameter than the bore of the barrel 166. The portion of the outer casing 10 adjacent to the opening 178 in the projectile stop 176 is weakened as illustrated at 180. Adjacent to the gun wad 172 is pinned a projectile 182 which includes a projectile body 184 having an outer diameter corresponding to the bore of the barrel 166. A projectile point 186 which is screwed into the projectile body has a flattened portion 188 rearwardly of the point thereon. Thus, it can be seen that when the black powder is ignited, the explosion resulting will release the projectile 182, force it forwardly with sufficient force to pierce the weakened portion 180 of the outer casing 10, and the projectile body 184 will come to rest against the projectile stop 176 with the projectile point 186 extending through the opening 178 and the outer casing weakened portion 180 as shown in Fig. 6. The projectile stop 176 acts as a safety feature to prevent the release of the projectile from the signal. Water can then pass into the casing 10 through the opening in the casing, due to the flattened portion 188 on the projectile.

Having described the apparatus in detail, the method of operation will now be described. Prior to launching the signal from the plane, the caps 136 at the top of the signal are removed. One or both of the clips 156 are likewise removed, depending upon the burning time desired. For the full burning time, the one clip 156 adjacent to the first candle assembly is removed along with the diaphragm cover 152, thereby exposing only the diaphragm 146. When the signal reaches the water, the impact of the water against the diaphragm 146 causes the diaphragm to flex inwardly, forcing the striker 158 against the primer 16 actuating it. The primer, in turn, ignites the lower end of the fuze 92, which burns upwardly within the tube 90 until the starter composition 98 at the top of the column is ignited. The gases and flame resulting ignite the pyrotechnic candle 82 and likewise burn out the starter container cover 96, the vapor barrier 103 and blow out the closure cup 108 at the top of the stack, permitting the vapor to emerge through the stack 102, which burns to produce the flame and smoke.

The pyrotechnic candle 82 is made of a pyrotechnic composition, well known in the art, pressed into a long, relatively slow burning candle which burns with the evolution of a vapor that reacts with atmospheric oxygen to yield large quantities of smoke and flame. For example, a suitable pyrotechnic candle will burn for a period of 30 minutes. When the candle has burned down to the location of the passage 112, the fuze 114 therein is ignited and acts to transfer the burning to the second candle by igniting the fuze 126 which in turn burns to the top of the second candle and ignites it through its starter composition similarly to the action of the first candle assembly.

When the second pyrotechnic assembly has burned down to the location of the passage 128, the fuse 130 therein is ignited and burns downwardly within the blocks 54, 38 and 18 to ignite the black powder 174

in the scuttle gun assembly. When the black powder is thus ignited, after completion of the burning of the second candle, the projectile 182 is ejected through the weakened portion 180 of the outer casing 10, piercing it as shown in Fig. 6 to permit the entry of water into the casing until signal sinks in the water after losing its buoyancy.

In the event that only one half of the burning time is desired, both clips 156 are removed prior to launching the signal and both diaphragm caps 152 and 154 are removed, exposing both diaphragms 146 and 148 to the water upon impact. Both diaphragms are thus actuated simultaneously to force the strikers 158 against the primers 16 to initiate simultaneously both the fuse 92 in

15 the first candle and fuses 131 and 126 in the second candle. Both candles are thus ignited simultaneously and burn together. At the end of the burning time the scuttle gun is actuated as heretofore described to sink the signal. When ignited, the short fuse 114 extending from the bottom of the first column to the second column is ignited, but the spit of fuse 114 into the cavity 112 is not sufficient to ignite the bottom end of the first column. When one half of the burning time is desired without the added smoke of two candles simultaneously, then only clip 156 and diaphragm cap 154 are removed thus igniting only the second candle.

It will thus be seen that this construction results in a floatlight that can be set to burn for one hour or for one-half hour, for example, as desired, followed by a 30 scuttling of the remaining inert casing. The construction described permits of the use of a metal casing surrounding each candle assembly that does not become consumed during the burning of the candle, and thus eliminates the need for wooden bodies as previously considered imperative to a successful signal.

It should be noted that one or more candle assemblies can be incorporated into the signal with minor modifications in the structure, although two candles are illustrated.

40 By reason of the buoyancy of the casing 10 and its very low center of gravity, the device will float upon the surface of the water and be maintained in a vertical position thereon, to which position it is immediately returned if displaced therefrom.

45 The temporary closure seals initially keep the water from entering the signal from the top, and the base member 12 and its joint with the casing 10 is watertight and prevents the entry of water from the lower end.

It will be obvious to those skilled in the art that 50 various changes may be made without departing from the spirit of the invention and therefore the invention is not limited to what is shown in the drawings and described in the specification but only as indicated in the appended claims.

55 What is claimed is:

1. A floatlight comprising an elongated outer casing, a first candle assembly supported within said outer casing and spaced therefrom, a second candle assembly supported within said outer casing and spaced therefrom and from said first candle assembly, each said candle assembly including an elongated pyrotechnic candle housed in a metallic casing enclosing said assembly, an inner central channel extending through said candles and a starter composition located at one end of said candles, 60 means for igniting said first pyrotechnic candle, a first fuse located within the channel of said first candle extending from said starter composition at one end of said candle to said igniting means at the other end of said candle, a second fuse leading from a point near the other end of said first candle through the channel in said second candle to its starter composition, a scuttle gun assembly including a propelling charge and a pointed projectile located within said outer casing, said scuttle gun assembly being adapted to fire the point of said projectile through said outer casing when actuated, and a

third fuse leading from the other end of said second candle to said scuttle gun assembly whereby upon completion of burning of said second candle said propelling charge is ignited by said third fuse to fire said projectile to pierce said outer casing by the head of said projectile and permit the entry of water therein for sinking said outer casing.

2. A floatlight adapted to burn while floating on water comprising an outer casing, a pyrotechnic candle located therein, means for igniting said candle, a scuttle gun assembly including a propelling charge and a pointed projectile located within said outer casing, said scuttle assembly being adapted to fire the point of said projectile through said outer casing when actuated, and a fuse connecting the end of said candle to said scuttle gun assembly whereby upon completion of burning of said candle said propelling charge is ignited by said fuse to fire said projectile to pierce said outer casing and permit the entry of water therein to sink said casing.

3. A floatlight comprising an elongated outer casing, a candle assembly supported within said outer casing and spaced therefrom, said candle assembly comprising a base block, a tubular metallic casing, said tubular metallic casing being attached at one end to said base block, an insulating lining tube adjacent said tubular metallic casing and inwardly thereof, a tube of fibrous cellulosic material adjacent said lining tube and inwardly thereof, and an elongated pyrotechnic candle within said last named tube, a closure enclosing the upper end of said tubular metallic casing thereby hermetically enclosing said candle assembly, an inner central channel extending through the length of said candle, a tube of fibrous cellulosic material located within said channel, an opening in alignment with said channel extending through said base block, a starter composition located at the upper end of said candle, a fuze extending from said starter composition through the length of said tube within said channel and through said opening in said base block, and means for igniting said fuze below said base block whereby said candle becomes ignited at its upper end and burns while said outer casing floats on the surface of a body of water.

4. A floatlight in accordance with claim 3 wherein two of said candle assemblies are supported within said outer casing and spaced therefrom, a fuse leading from the lower end of the first of said candle assemblies to the lower end of the second of said candle assemblies for conducting the flame from said first candle to the fuze at the lower end of said second candle assembly, and said igniting means comprises a first igniting means for igniting the fuse at the lower end of said first candle assembly and a second igniting means for igniting the fuse at the lower end of said second candle assembly whereby when said first igniting means is actuated said candles burn consecutively, when said second igniting means is actuated only said second candle assembly burns and when said first and second igniting means are ignited simultaneously, both said candle assemblies will burn simultaneously.

5. A floatlight in accordance with claim 3 including a scuttle gun assembly comprising a propelling charge and a pointed projectile located within said outer casing below said candle assembly, said scuttle gun assembly being adapted to fire the point of said projectile through said outer casing when actuated and a fuse connecting the lower end of said candle to said scuttle gun assembly whereby upon completion of burning of said candle said propelling charge is ignited by said fuse to fire said projectile to pierce said outer casing and permit the entry of water therein for sinking said outer casing.

6. A floatlight in accordance with claim 5 wherein means are provided in said scuttle gun assembly to prevent the complete ejection of said projectile therefrom yet permitting the piercing of said outer casing by the point of said projectile.
